UNITED STATES PATENT OFFICE.

LEWIS KALLING, OF BALTIMORE, MARYLAND.

SEALING-CAP FOR BOTTLES.

No. 832,888.

Specification of Letters Patent. Patented March 24, 1908.

Application filed November 22, 1906. Serial No. 344,540.

To all whom it may concern:

Be it known that I, LEWIS KALLING, of the city of Baltimore and State of Maryland, have invented certain Improvements in Sealing-Caps for Bottles, of which the following is a specification.

This invention relates to improvements in sealing caps for bottles, of the description in which the cap is secured to the bottle head by a reduction in its diameter, and which contains a compressible joint-forming appliance consisting either of a ring or a disk as may be desired.

The said invention consists in a peculiar formation of the sealing cap whereby the joint-forming appliance is held in contact with the crown of the cap, and the vertical wall or flange of the cap given a certain elasticity which adapts it to fit bottle heads differing in diameter, as will hereinafter fully appear.

In the further description of the said invention which follows, reference is made to the accompanying drawing forming a part hereof, and in which,

Figure 1 is an enlarged vertical central section of the upper part of a bottle provided with a sealing cap constructed in accordance with the present invention, and showing the cap as it appears before the sealing operation. Fig. 2 is a view similar to Fig. 1 except that the cap is shown as it appears subsequent to the sealing operation. Fig. 3 is a top view of the blank from which the sealing cap is formed. Fig. 4 is a top view of the cap as shown in Fig. 2. Fig. 5 is a top view of one form of the joint-forming appliance or gasket.

Referring now to the drawing, 1 is the bottle head having the annular lip or shoulder *a*.

The sealing cap comprises the crown *b* and the flange *c* which latter engages with the lip *a* and effects the attachment of the cap to the bottle head.

The joint-forming gasket is denoted by 2, and as one object of the invention is to secure the said gasket in contact with the underside of the crown, the flange *c* is provided with a multiplicity of projections or prongs *d* which extend radially from the blank 3 shown in Fig. 3, and which are ultimately introverted or turned inward so as to produce a flexible and compressible inner surface or lining in the flange *c* of the cap, as shown in Figs. 1 and 2.

By reference to Figs. 1 and 2 it will be seen that the joint-forming gasket is a flat device, which in Fig. 1 is shown as held against the inner surface of the crown by the points of 60 the prongs *d*.

In the sealing operation which consists in closing the cap over the bottle head, the prongs *d* being independent and yielding devices, separately adapt themselves to the 65 contour of the parts of the bottle head with which they are brought in contact; and the prongs at the curvature *f* where they are wider and less flexible than at the points, are forced slightly under the annular lip or 70 shoulder *a* and form a system of locks which offer resistance to the removal of the cap.

It is within the scope of the invention to use either an annular or a disk joint-forming gasket; and also to form the prongs *d* of any 75 desired shape, and length with respect to the depth of the flange, as the invention consists in the formation of the cap with a flange having a double elastic wall, or a flange having an inner wall or lining which has a 80 greater elasticity than the outer wall whereby it is adapted to readily adjust itself to the shape of the bottle head, and in doing so produce with the annular lip of the bottle head, a system of locks.

85

I claim as my invention:

1. In combination with a sealing cap comprising a crown and a pendent flange adapted for attachment to a bottle head provided with an annular lip or shoulder, a 90 joint-forming gasket placed within the cap and in contact with the crown thereof, and a multiplicity of prongs which extend from the edge of the said flange and have their points in contact with the said gasket whereby the same is held in place, substantially as specified.

2. In combination with a bottle having an annular lip or shoulder a sealing cap comprising a crown and a pendent flange provided with a multiplicity of prongs which are inturned so as to produce an inner wall or lining for the flange which is expandable and compressible independently of the flange proper, and a joint-forming gasket which is 105 held within the cap by the said prongs, substantially as specified.

LEWIS KALLING.
